United States Patent Office

Des. 179,713
Patented Feb. 12, 1957

179,713

POWER BOAT

Ronald A. White, Coconut Grove, Fla.

Application August 3, 1955, Serial No. 37,311

Term of patent 7 years

(Cl. D71—1)

Fig. 1

Fig. 2

Fig. 3

Fig. 1 is a top plan view of a power boat embodying my new design.

Fig. 2 is a side elevational view and is identical to the side not shown.

Fig. 3 is a front elevational view thereof.

I claim:

The ornamental design for a power boat, as shown and described.
